FLASHING

Leo Friedberg, New Brunswick, N. J.

Application July 31, 1934, Serial No. 737,819

21 Claims. (Cl. 72—127)

My invention relates to flashings and more particularly to through wall flashings of sheet metal which are adapted to be imbedded in the usual bonding mortar between courses of bricks, 5 etc. More specifically my invention relates to anchoring means for providing a more perfect mechanical bond between the flashing sheets and the courses of masonry, said means being so constructed and arranged as to serve as clips for holding weep-hole forming wicks at desired points on the sheets so as to extend substantially transversely thereof and in contact therewith.

The present invention also relates to a novel form of interlocking means for joining the transverse edge portions of adjacent through wall flashing sheets so as to effectively prevent the passage of moisture between the overlapping portions of the sheets and into the masonry wall below the flashing.

An object of my invention is to provide a joint of the character briefly described which may be readily assembled on the job and which when assembled will be sufficiently rigid to maintain the sections of flashing in desired position while placing mortar thereover, yet which will permit slight relative movement of the sections under expansion and contraction without causing the joints to open.

A further object is to provide an interlocking means of the type described which will effectively serve as an anchoring means for the flashings whereby the flashing sections may expand or contract between the courses of masonry without breaking its bond with the mortar.

Other objects and advantages will become apparent from a consideration of the following detailed description taken in connection with the accompanying drawing wherein:

Fig. 1 is a plan view of a portion of two flashing sections showing my improved means for locking the sections together and anchoring or bonding the flashing to the masonry.

Fig. 2 is a transverse section taken on line 2—2 of Fig. 1.

Fig. 3 is an enlarged longitudinal sectional view taken on line 3—3 of Fig. 1 showing in dotted and full lines the relative positions of two flashing sections when locking them together.

Fig. 4 is a longitudinal sectional view of a portion of a flashing section showing in perspective a modified form of anchor and wick clipping means secured to the flashing, and

Fig. 5 is a further sectional view through two overlapping flashing sections showing a modified 55 form of interlocking means for the sections, one

of the elements of which, serves to clip a weep-hole forming wick to the flashing.

In the drawing A—B, indicate two sections of flashing each composed preferably of corrugated sheet metal and interlocked in overlapping relationship, and C, cotton wicks of rope-like formation which are secured to the sheets to extend substantially transversely thereof. The flashing sheets and wicks may be as described and claimed in Abram B. Friedberg Patents No. 1,935,116, November 14, 1933 and No. 1,976,166, October 9 10 1934, and therefore need no particular description herein.

I have found that joints heretofore employed for securing the transverse edge portions of flashing sheets will not permit of any variation in overlap of adjacent sections and are therefore often difficult to unite on the job. As a result of this lack of flexibility of the interlocks or joints of former flashing sheets the sections are often so 15 carelessly joined as to totally destroy the effect of the flashing. For this reason architects often specify that the overlapping portions of adjacent flashing sheets must be soldered.

While a soldered joint may effectively hold the 20 sections of flashing in proper relationship when placing mortar thereover, such a joint will not permit of any relative movement of the flashing sections in use between the courses of masonry, without breaking the joint and destroying the 25 usefulness thereof.

The joint of my invention overcomes the objections above pointed out and further serves as a means for anchoring the flashing sheets in the mortar. In carrying this into effect I provide, 30 along one transverse edge of each flashing sheet, an upwardly and outwardly inclined strip 5, which strip terminates in a relatively shorter horizontal hook portion 6 adapted to overlay the upper surface of an adjacent flashing sheet and in spaced 35 relation thereto. This upwardly inclined portion 5, which is bent under and upon itself at its outer free end to provide the horizontal flat hook 6, may constitute an angled part of the flashing sheet but as shown comprises a separate strip 40 soldered or otherwise permanently secured to the transverse edge portion of the sheet. At a point 45 inwardly spaced from the opposite transverse edge of each sheet I provide an upstanding strip 7 which extends transversely across the sheet. The upper edge portion of this strip 7 is bent over to form a horizontal lip 8 which is adapted 50 to be engaged by the horizontal hook portion 6 of an adjacent flashing sheet so as to lock the sheets in overlapping relationship from edge to 55

edge of the sheets and at a point spaced above the upper surface of the sheets. An expansion joint is thus formed which will remain perfectly moisture-proof regardless of stresses and strains imposed on the sheets in use in a masonry structure and the overlapping edge portions of the sheets are held bonded to the mortar in which they are embedded by the overhanging anchor construction of the joint which extends up into the 10 mortar.

On the upper face of the sheets and between these interlocking elements of the joints I secure two or more rope-like wicks C to each section of flashing A-B so as to extend transversely of the 15 sheets from edge to edge thereof as is clearly shown and described in the patent and application above referred to. In the present invention however, I so construct the clips 9 which secure the wicks to the sheets as to provide means for 20 anchoring the intermediate portions of the sheets in the bonding mortar.

As shown in Figs. 1, 2 and 3 these anchor clips 9 comprise relatively short sections of sheet metal, each of which is bent into the form of oppositely and outwardly facing troughs 10, the vertical webs of which are spaced substantially the width of a wick C by the reversely bent integral portion 11 of the upper, oppositely extending, flanges of the troughs. The lower flanges 30 of the troughed sides of the anchor clips 9 serve as means for securing the clips to the faces of the flashing sheets, as by soldering.

As shown in the Friedberg patent, above referred to, it is desirable that the clips be secured 35 to the upper face of a flashing section or sheet in at least two laterally spaced, wick holding rows extending transversely of the sheet and from the upper to the lower edges thereof. In the present invention I make use of the clips 9' 40 as means for also anchoring the under side of each flashing sheet in the bonding mortar. As indicated in Fig. 4 it has been found desirable to arrange the rows of clips 9' intermediate the rows of clips 9 which are secured to the opposite face 45 of the sheet. By this arrangement the bonding mortar enters the channeled sides of the clips 9 and 9', when embedded therein, to interlock and key the mortar above the flashing sheet with the mortar below the sheet. In this way the bond 50 between the masonry above and below the flashing is maintained unbroken irrespective of stresses and strains set up in the sheets or masonry in use.

In Fig. 4 I have shown a slightly different form 55 of anchor clip 12 and 12'. These clips comprise relatively short sections of upwardly facing channeled sheet metal, the side flanges 13 and 13' of which are outwardly flared so as to extend at approximately 45° to the face of the sheet to 60 which they are secured, as by soldering. As in the case of the anchor clips shown in Figs. 1, 2 and 3 these clips 12 and 12' may be used solely for keying the flashing to the mortar above and below the sheet or as a combined key or anchor 65 and wick holding clip by cutting and bending in side portions 14 of the outwardly flared flanges 13 so as to grip and hold the wick C' adjacent the upper face of the flashing.

In Fig. 5 I have shown a modified form of interlocking means for two flashing sections. In 70 this form, as in the preferred form shown in Figs. 1, 2 and 3, a metal strip 15 is soldered or otherwise secured to the upper face of a flashing section inwardly of one transverse edge so as to 75 extend at right angles to the sheet. The upper

end portion 16 of the strip is preferably corrugated in a direction transversely of the sheet and bent over so as to extend slightly downwardly over the outer portion of the sheet to which it is attached and towards the transverse edge thereof. The adjacent transverse edge of a section of flashing to be secured in overlapping relation with the section so equipped, is preferably turned upwardly to provide a vertical flange 17 which is adapted to be locked under the substantially horizontal flange 16 of the vertical strip 15 thereby firmly holding the adjacent edge portions of the two flashing sheets in interlocked, overlapping relationship. 10

In addition to providing an efficient and economical expansion joint for two overlapping sections of flashing the lower inwardly flanged supporting edge of the vertical strip 15 may be provided with clip portions in the form of fingers 19 to be bent around a weep-hole forming wick C' 20 laid transversely across the sheet adjacent the inner side of the strip 15. 15

While several illustrative embodiments of the invention have been described somewhat in detail, it is not intended to limit the scope of the 25 invention thereby or otherwise than by the terms of the appended claims.

What I claim is:

1. A flashing composed of at least two sheet metal sections, and an expansion joint connecting 30 said sections with substantial side portions thereof in face to face overlapping relationship, said joint comprising a transverse strip upstanding from each of said flashing sections, and flange means at the upper edge of one of said strips 35 interlocking with the upper edge portion of the other of said strips.

2. A flashing composed of at least two sheet metal sections, and an expansion joint connecting 40 said sections with substantial side portions thereof in face to face overlapping relationship, said joint comprising a transverse strip upstanding from each of said flashing sections, flange means at the upper edge of one of said strips, and hook means at the upper end portion of said 45 other strip adapted to interlock with said flange means.

3. A flashing composed of at least two sheet metal sections, and an expansion joint connecting 50 said sections with substantial side portions thereof in face to face overlapping relationship, said joint comprising a transverse strip upstanding from each of said flashing sections, and flange means at the upper edge of one of said strips, said other strip having an upwardly inclined body 55 portion terminating in a horizontally disposed hook adapted to interlock with said flange means.

4. A flashing composed of at least two sheet metal sections, and an expansion joint connecting 60 said sections in overlapping relationship, said joint comprising a transverse strip upstanding from each of said flashing sections, flange means at the upper edge of one of said strips interlocking with the upper edge portion of the other strip, and means extending laterally and upwardly from 65 the lower end of said flanged strip for fastening said strip to the face of the flashing section and securing a weep-hole forming wick in position adjacent the intersection of the strip and flashing section. 70

5. A flashing composed of at least two sheet metal sections the adjacent transverse side portions of which are adapted to be connected in face to face overlapping relationship, one of said sections having a laterally flanged, upstanding 75

metal strip secured to its upper face inwardly of a transverse edge, and said other section having an upturned transverse edge portion adapted to hook under the laterally flanged strip of said first mentioned section.

6. A flashing composed of at least two transversely corrugated sheet metal sections the adjacent transverse edge portions of which are adapted to be connected in overlapping, registering relationship, one of said sections having an upstanding strip extending transversely across the sheet, the upper edge portion of which strip is laterally turned and transversely corrugated to provide a locking flange overlaying the corrugated side portion of the sheet, and said other section having an upturned transverse edge portion adapted to engage under the corrugated flanged strip of said first mentioned section, whereby to retain the corrugations of the overlapping portions of the sheets in nested relationship preventing displacement of the flashing sections in use.

7. In a through wall flashing sheet, a strip of sheet metal having longitudinally extending portions thereof bent over at substantially right angles to the intermediate web portion of the strip to provide flanges, one of said flanges being connected to said sheet to extend transversely thereof and supporting the web portion of the strip in vertical position with said other flange overlaying said sheet, and means formed in part with said strip for securing a weep-hole forming wick to said flashing sheet.

8. In a through wall flashing sheet having a weep-hole forming wick extending transversely thereof, anchor clips therefor comprising a strip of sheet metal having longitudinal portions thereof reversely bent on opposite sides of its center to provide oppositely facing channels, the lower flanged portions of which are adapted to be secured to said flashing sheet on opposite sides of said wick.

9. A sheet metal through wall flashing sheet having a weep-hole forming wick extending substantially transversely thereof, and bifurcated clips secured to said sheet and engaging the sides of said wick to retain the wick adjacent the surface of the sheet, said clip having a side portion overlaying the adjacent surface of the sheet to provide a bonding mortar receiving and locking key for the sheet.

10. A sheet metal through wall flashing sheet having anchor clip means secured to one face thereof, each of said clip means having parallel side portions secured at laterally spaced points to said sheet and intermediate portions spaced from said sheet and cooperating therewith to provide a wick securing clip and a three point mortar receiving and locking key for the sheet.

11. A sheet metal through wall flashing sheet having mortar-receiving and anchoring means secured to one face thereof, said means having an upstanding web portion extending in a direction transversely of the sheet, the upper edge of which is bent at substantially right angles to the web, and means for securing a weep hole forming means adjacent said web.

12. In a through wall flashing sheet, bifurcated mortar anchoring means secured to said sheet, said means having oppositely extending side flange portions overlaying the surface of said sheet to opposite sides of said means and extending inwardly over the space between said means.

13. In a through wall flashing sheet, mortar anchoring clips secured to one face thereof, said clips comprising sheet metal strips bent into substantial U-shape, the side portions of which extend out over the surface of the sheet on opposite sides of said clips, and means for securing a weep hole forming means thereto.

14. In a through wall flashing sheet, mortar anchoring clips secured to one face thereof, each of said clips comprising a sheet metal strip bent into substantial U-shape with the spaced side portions thereof extending over the surface of the sheet on opposite sides of said clip, at least one of said side portions having a finger bendable toward the other side portion to provide with said side portions a wick securing clip.

15. An anchor clip for a flashing sheet, comprising an inverted trough shaped member having a flat top and sides bent under the top to form double-wall side flanges the vertical webs of which extend at right-angles from the top to form a support therefor and for attachment to a flashing sheet.

16. An anchor clip for a flashing sheet, comprising a flat top member provided at each side thereof with integral trough shaped members bent under the top member and opening outwardly, the side walls of the trough shaped member opposite the top member serving as supports for the top member and for attachment to a flashing sheet.

17. An anchor clip for a flashing sheet, comprising a channel member having a top portion substantially wider than the channel portion to provide overhanging flanges, the free side edges of the channel walls extending outwardly for attachment to a flashing sheet.

18. In combination a flashing sheet, an anchor clip attached thereto, said clip comprising a channel shaped member having a top portion of substantially greater width than the channel portion to provide outwardly extending overhanging flanges, the side walls of the channel member being bent outwardly at their free edges to form bases which are attached to the flashing sheet.

19. A through wall flashing sheet having transversely extending anchor clips secured to opposite sides thereof, the anchor clips on one side of the flashing sheet being disposed intermediate those on the opposite side, and weep-hole forming wicks held between certain of said anchor clips and said sheet.

20. In a through wall flashing sheet having weep hole forming wicks extending across the face thereof, mortar anchoring keys extending from opposite faces of said sheet, said keys having means to secure said wicks to said sheet.

21. A flashing composed of at least two sheet metal sections the adjacent side portions of which are transversely corrugated, and an expansion joint connecting the corrugated side portions of said sections in face to face overlapping relationship, said joint comprising transversely extending means upstanding from the upper face of one flashing section inwardly of a transverse edge thereof, and transversely extending means upstanding from the transverse edge of the overlying flashing section adapted to interlock with said first mentioned means.

LEO FRIEDBERG.
